UNITED STATES PATENT OFFICE.

JOHN B. GABRIELSON, OF SPRINGVILLE, NEW YORK.

RADIATOR.

1,335,890.

Specification of Letters Patent. Patented Apr. 6, 1920.

Application filed March 27, 1918. Serial No. 224,938.

To all whom it may concern:

Be it known that I, JOHN B. GABRIELSON, a subject of the King of Sweden, residing at Springville, in the county of Erie and State 5 of New York, have invented certain new and useful Improvements in Radiators, of which the following, taken in connection with the accompanying drawings, is a specification.

10 The invention relates to radiators for motor driven vehicles; and the object of the improvement is, first, to provide a radiator core construction in which the thin sheet metal which forms the walls of the zigzag 15 water ways is corrugated between contacting points in order to stiffen and strengthen the same thereby enabling the use of extremely thin sheet metal such as copper; and secondly, to provide alternate zigzag narrow 20 spacing strips between the corrugated sheet metal water ways at each end which are cross corrugated between contacting points to stiffen said strips, thereby providing a larger circulation of air and radiating 25 surface within the radiator core and around said zigzag water ways to aid in cooling the water; and the invention consists in the novel features and combinations hereinafter set forth and claimed.

30 In the drawing, Figure 1 is a perspective view of a portion of the radiator core showing the general contour of the zigzag spaced water ways and the narrow spacing strips at each end of the air flues with the double 35 cross corrugation in said strips to stiffen and strengthen the same as well as beautify the front design; and Fig. 2 is a front elevation of the same. Fig. 3 is a sectional view of said water ways adjacent the inner edge of 40 one of the double corrugated spacing strips. Fig. 4 is a perspective view of one of the corrugated metal sheets forming one of the sides of the spaced water ways; and Fig. 5 is a perspective view of one of the double 45 corrugated spacing strips.

Like characters of reference refer to corresponding parts in the several views.

The numeral 10 designates the radiator core which is composed of zigzag sheet metal 50 water ways 11 which extend from top to bottom of said radiator core and are composed of oppositely placed sheets 12 which have the crosswise corrugations 13 therein from edge to edge of said strips, the central portion 55 14 being bent sufficiently sidewise in opposite directions to form the opening 15 for

the zigzag water way 11. Edge portions 16 of the contacting sheets 12 each side of the opening 15 fit firmly against one another so as to be firmly attached to one another by 60 soldering on both the inner and outer edges of the zigzag strips 12.

The zigzag water ways 11 are spaced from one another by means of the zigzag strips 17 which are preferably somewhat 65 wider than the contacting edge portions 16 of the strips 12 so as to brace the water way 11 firmly and at the same time provide larger circulation of air between said water ways and a larger amount of radiating surface, at the same time saving an appreciable quantity of the costly sheet copper in said spacing strip; that is, if said spacing strip were to extend from the front to the rear edges of said core. The spacing strips 17 70 are made in zigzag form the same as the sheets 12 of the water ways 11 and have the corrugations 18 therein corresponding to the corrugations 13 in the sheets 12 between the contacting surfaces 19 of the sheets 12 80 and 20 of the strips 17.

The contacting surfaces 19 are preferably made flat so as to brace firmly against one another, the central portions of said contacting surfaces 19 of the water ways 11 being 85 exposed to the air in addition to the corrugated sides between said contacting surfaces. The spacing strips 17 also have grooves or corrugations 21 crosswise of the corrugated side 18 between the flat contacting surfaces 90 20 to further stiffen said strip 17 and also to present a pleasing design for the front of the radiator core.

The core is preferably made as hereinbefore stated from extremely thin sheet copper, usually about five-thousandths of an inch in thickness. The corrugations 13, 18 and 21 are pressed into the thin sheet copper by suitable dies which also form the 100 sidewise bends 14 for the opening 15 of the water ways 11. The zigzag sheets 12 and zigzag spacing strips 17 are assembled in a suitable frame which clamps the parts firmly in the assembled form, so that the contacting edges 16 and portions of the strips 17 may be dipped in the solder flux thereby rigidly attaching all the parts to one another in the desired position ready for insertion in a suitable casing.

I claim as new:—

110
In a radiator core, pairs of zigzag sheets having horizontal flat parts and having

their edge portions contacting and secured together, the divergent parts of said edge portions of the sheets being formed with nesting longitudinal corrugations, and zig-zag spacing strips of slightly greater width than the lengths of said contacting edge portions of the pairs of sheets having corresponding flat parts seated upon the respective flat parts of one of the sheets and extending over and beyond the inner ends of said contacting portions, the pairs of sheets forming one half and the spacing strips the other half of hexagonal air cells, the other

sheet of each pair being bent outwardly from points between the front and rear edges of the spacing strips to form water ways, the divergent parts of the spacing strips being formed with longitudinal and with centrally transverse corrugations.

In testimony whereof I have affixed my signature in the presence of two witnesses.

JOHN B. GABRIELSON.
